2,538,626

UPWARD ACTING DOOR CONSTRUCTION

Henry Hans Olsen, Detroit, Mich., assignor to
 Crawford Door Company, Detroit, Mich., a corporation of Michigan

Application July 23, 1947, Serial No. 762,933

5 Claims. (Cl. 160—201)

1

This invention relates to an upward acting closure assembly especially suitable for garage door installations and the like and specifically deals with an articulated upward acting door assembly which does not require head room above the door opening and is equipped with cable guide brackets arranged to minimize slamming of the door and to initiate opening movement of the door.

This application is a continuation in part of my copending application, Serial No. 725,659, filed January 31, 1947, entitled: "Upward Acting Door Construction," now abandoned.

In the aforesaid parent application Serial No. 725,659, spring-impelled cables are guided around sheaves positioned closely adjacent the door opening and above the top of the closed door. The cables have a substantially straight upward pull on the door for counterbalancing the weight of the door. In accordance with the present invention, the cable guide sheaves are positioned inwardly from the door opening so that the cables will have an inward as well as an upward pull on the door. The cable run between the guide sheaves and the bottom of the door is deflected by door-mounted cable guide brackets arranged to pull the cables in an out of the way position and provide a cable run substantially parallel with the lower portion of the door and a second cable run inclined from the lower portion of the top section of the door to the guide sheaves. The top section of the door has the top edge thereof supported on a pair of horizontal tracks extending inwardly from the top of the door opening. These tracks can be positioned immediately beneath the ceiling of the building and the door does not require head room above the door opening. The other portions of the door are supported in a second pair of tracks which has vertical legs at the sides of the doorway, curved portions extending inwardly from the doorway, and horizontal legs immediately under the first pair of horizontal tracks. As the top of the top door section moves straight inwardly along the horizontal tracks, the other portions of the door are guided in the second pair of tracks for upward and inward movement.

A feature of the invention resides in the mounting of the cable bracket on the top door section above the hinge axis between this section and the adjacent door section so that the cables will have an inward pull on the top door section tending to cock it away from closed position, thereupon initiating opening movement

5 of the door. The door is conveniently locked in closed position by means of a spring-pressed locking bolt on the top door section coacting with a keeper fixed on the building. Since the cables exert an inward pull on the top door section, they are also effective to prevent slamming of the door into closed position when the door is lowered. The desired snubbing action can be controlled by the position of the cable pick-up brackets relative to the hinge axis between the door sections.

10 It is, then, an object of this invention to provide an upward acting door construction of the type disclosed in my parent application Serial No. 725,659 but equipped with cable pick-up brackets effective to initiate opening movement of the door and to prevent slamming of the door into closed position.

15 Another object of the invention is to provide an upward acting door assembly which does not require head room above the door opening and which has spring-impelled door counterbalancing cables deflected by door-carried guides to produce the desired force components on the door.

20 Another object of the invention is to provide a cable-impelled closure assembly with cable guide brackets which hold the cables in an out of the way position.

25 Another object of the invention is to provide a no head room upward acting closure assembly with spring-impelled counterbalancing cables and cable guide brackets on the closure so arranged as to deflect the cables into angled runs having desired force components on the closure.

30 Another object of the invention is to provide a garage door or the like composed of hinged-together sections and having cable pick-up brackets on the top section arranged relative to the hinge axis between this section and its adjacent section so that cables passed thereover will prevent slamming of the top section into closed position.

35 A further specific object of the invention is to provide a garage door of the articulated type wherein the top door section has the top edge thereof mounted for straight inward movement on a first pair of horizontal tracks and wherein the other door sections are mounted for movement on a second pair of tracks while the weight of the door is counterbalanced by spring-impelled cables so directed as to exert an inward pull on the top door section for initiating opening movement of the door and for resisting slamming of the door into closed position.

40 45 50 55 Other and further objects of the invention will

2

be apparent to those skilled in the art from the following detailed description of the annexed sheets of drawings which, by way of a preferred example only, illustrate one embodiment of the invention.

On the drawings:

Figure 1 is an inside broken elevational view of the door assembly of this invention showing the door in closed position.

Figure 2 is a vertical cross-sectional view taken along the line II—II of Figure 1.

Figure 3 is a view similar to Figure 2 but illustrating three positions of the door as it moves from the closed position of Figure 2 to the fully opened position.

Figure 4 is an enlarged fragmentary horizontal cross-sectional view taken along the line IV—IV of Figure 1.

Figure 5 is an enlarged fragmentary horizontal cross-sectional view taken along the line V—V of Figure 1.

Figure 6 is a fragmentary top plan view along the line VI—VI of Figure 2.

Figure 7 is a fragmentary somewhat diagrammatic side elevational view illustrating the snubbing action on the door as it is moved to closed position.

As shown on the drawings:

In Figure 1 the reference numeral 10 designates a portion of a building, such as a garage, having a doorway 11 defined by a top lintel 12, side door jambs 13, 13 and a floor 14. The door jambs 13, as best shown in Figure 4, carry weatherstrips such as 15 projecting into the doorway 11 and a door 16 is sized to close the doorway 11 between the door jambs 13 so that its outer face will abut the weatherstrips 15. The upper edge of the door has its outer face abut the inner face of the lintel 12, or alternately, a weatherstrip carried by the lintel.

The door 16 is preferably composed of two hinged together sections or panels including a top section 16a and a bottom section 16b connected in articulate relation by hinges 17, 17.

The building 10 has a ceiling 18 which, in accordance with this invention, need not be materially higher than the top of the doorway, to accommodate full operation of the door.

Two sets of tracks are provided for the door including a first set composed of horizontal tracks 19, 19 lying close to the ceiling 18 and suspended at their rear ends on ceiling-carried brackets 20. The front ends of these horizontal tracks 19 are attached to the door jambs 13 by means of brackets 21. Rollers 22 are mounted in the tracks 19 and have axles 23 projecting laterally from brackets 24 at the upper corners of the door section 16a. The brackets 24, as shown in Figure 1, are secured on the inner face of the door section 16a and have flanges overlying the side edges of the section so that the axles 23 project laterally from these side edges. The rollers 22 mount the top edge of the upper door section 16a for movement along the horizontal tracks 19.

The second set of tracks include tracks 25, 25 each with a vertical leg portion 25a, a horizontal leg portion 25b, and a curved connecting portion 25c. The vertical portion 25a of each track 25 is mounted on a door jamb 13 by means of brackets 26 which carry the track portion along the inner face of the door jamb. The horizontal track sections 25b are suspended under the horizontal tracks 19 by means of brackets 27 at the rear ends of the portions 25b and by means of gusset plates

28 depending from the tracks 19 to partially overlie the curved track portion 25c and the inner end of the horizontal portion 25b. As shown in Figure 2, the portion 25b can be separate from the portion 25c and joined therewith by the gusset plate 28 which has rivets or pins 29 extending into both portions. The track portion 25b, as best shown in Figure 1, is directly aligned beneath the horizontal tracks 19.

The lower corners of the bottom door section 16b have brackets 30 secured thereon with flanges extending over the side edges of the door and carrying axles 31 (Figure 4) on which rollers 32 are mounted. The rollers 32 ride in the second set of tracks 25. These brackets 30 also have flanges 30a extending inwardly of the tracks 25 and equipped with cable anchors 33 beyond the tracks 25.

The hinges 17 for the door sections 16a and 16b include overlapping leaves on the side edges of the door joined together by axles 34 for rollers 35 which ride in the tracks 25. These axles 34 thus form the turning axis for the door sections.

The rear ends of the horizontal tracks 19 carry notched strips 36 which extend in spaced parallel relation outwardly from the outer faces of the tracks to receive the rear ends of coil springs 37. These springs 37 have the end turns thereof telescoped over the strips 36 and selectively anchored in a notch thereof so that the tension of the springs can be adjusted.

The front ends of the springs 37 are connected to clevises 38. Grooved guide sheaves 39 are rotatably mounted on pins 40 of the clevises 38. The guide sheaves 39 are thus spring tensioned by the springs 37 which tend to pull them toward the rear ends of the tracks 19.

As best shown in Figure 6, each gusset plate 28 has an offset portion 28a outwardly from the track 19 and carrying a pin 41 on which a grooved sheave or roller 42 is rotatably mounted. The sheaves 42 are thus mounted for rotation about fixed axes provided by the pins 41 and are positioned at the sides of the tracks 19 in spaced relation inwardly from the doorway 11.

A cable 43 is provided at each side of the door and has one end thereof secured to an anchor 33. The cables are trained over the sheaves 42 and around the sheaves 39 with their other ends being anchored at 44 in the offset portions of the gusset plates 28.

With the door in the closed position of Figure 2, the cable 43 would normally extend along an inclined path from the anchor 33 to the sheave 42. In accordance with this invention, however, a cable pick-up bracket 45 is fixedly mounted on the inner face of the top door section 16a near the bottom edge thereof and projects laterally beyond the side edge of the door to overlie the cable 43. A bracket 45 is provided for each cable 43 and, as best shown in Figure 5, each bracket 45 has a leg portion 45a secured to the inner face of the door section 16a by means of screws 46 and a U-shaped portion 45b extending around the track 25 and terminating in a recessed lip 45c receiving the cable 43 in the recess thereof. The lip 45c of the bracket holds the cable 43 in alignment with the side edge of the door so that when the door is in closed position the cable has a substantially vertical run from the anchor 33 to the bracket 45 and an inclined run from the bracket 45 to the sheave 42.

As best shown in Figure 1, the brackets 45 are positioned slightly above the axles 34 forming

the turning axis for the door sections 16a and 16b. Since the spring-impelled sheaves 39 tend to pull the cable rearwardly over the sheaves 42, the cable tends to raise the door in the tracks 25. This raising action, however, cannot take place until the upper door section 16a is moved inwardly from a dead center position where the rollers 22 are directly above the rollers 35. In other words, a straight lifting action on the door will be resisted by the rollers 22 which will abut the top flanges of the tracks 19. Therefore, in order to open the door, the top door section 16a must be moved out of vertical alignment with the bottom section 16b and this movement can only occur by moving the rollers 22 rearwardly in the tracks 19. When the door section 16a is cocked or tilted relative to the section 16b, an upward pull on the section 16b will raise the both sections while increasing the angle of tilt between the sections as illustrated in the various positions of the door shown in Figure 3. The door thus initially moves from the solid line position of Figure 2 to the dotted position of Figure 3 with the section 16b tilted slightly relative to the section 16a. It will be noted that this tilting of the section 16a requires considerable inward movement of the top portion of the section, but the bottom door section 16b does not appreciably raise. As the door continues to move upward to the solid line position of Figure 3, the upper section 16a assumes a substantially horizontal position with the rollers 22 moving rearwardly in the tracks 19 and the rollers 35 moving around the curved portion 25c of the tracks 25 while the rollers 32 rise to the upper ends of the vertical portions 25a of these tracks. The door continues to rise and move rearwardly to the dot-dash line position also shown in Figure 3, where the bottom edge of the section 16b is immediately below the sheave 42 and the top edge of the section 16a is at the rear of the horizontal tracks 19.

The brackets 45 of this invention, as best illustrated in Figure 7, are effective to have the cables 43 produce an initial inward pulling action on the door section 16a since the brackets are above the tilting axis of the door section 16a provided by the axles 34 thereby providing short lever arms perpendicular to the tilting axis of the door section and between the axis and the brackets 45. This inward pulling action tends to cock the door section 16a relative to the door section 16b so that the counterbalancing springs 37 will be effective to pull the cables 43 for raising the door to its open position.

Conversely, when the door is pulled from an open position downwardly to its closed vertical position, there will be a resulting inward force tending to snub movement of the door section 16a into vertical alignment with the section 16b, and this snubbing action prevents slamming of the door section 16a into its closed position. Thus, as illustrated by the arrows in Figure 7, when the door section is pulled downwardly as indicated by the arrow A, the door section 16a must move in the direction indicated by the arrow B, but, at the same time, movement in the direction B is opposed by a small component of force in the direction of the arrow C. The proportion of this force relative to the total spring load can be adjusted by varying the spacial relation of the brackets 45 from the turning axis of the door sections on the axles 34.

In order to lock the door 16 in closed vertical position, it is merely necessary to provide a

spring-pressed bolt 47 on the inner face of the door section 16a at the upper edge thereof for projecting above this upper edge into a keeper 48 on the ceiling of the building. The bolt 47 can be retracted out of the keeper by manual actuation of a pull chain 49 on a lever 50 of a rotating handle 51. When the handle 51 is turned to retract the bolt out of its keeper, the component of force in the direction of the arrow C of Figure 7 is preferably sufficient to cock the door section 16a relative to the section 16b so that the spring action will be effective to counterbalance the door for easy opening movement to its full overhead position. Movement beyond full overhead position is snubbed by virtue of the cable anchor 33 passing beyond alignment with the sheave 42 necessitating elongation of the spring 37. When the door is pulled downwardly from its open position, the springs 37 coast with the brackets 45 to have an inward pull on the door section 16a so that it will not slam into closed position.

From the above descriptions it will be evident that the invention provides an upward acting counterbalanced closure construction which is automatically snubbed against slamming when closed, and is automatically released to an opening position when unlocked.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. An upward acting door construction comprising a pair of hinged-together door sections, rollers mounted on the sides of said sections, tracks carrying said rollers for guiding the sections between a closed vertical position and an open overhead horizontal position, guide sheaves fixedly positioned inwardly of the closed position of the upper end of the door, spring-tensioned cables trained over said sheaves and anchored at their lower ends to the lower portion of the bottom door section, the spring tension on said cables tending to hold said cables in inwardly inclined straight runs between said sheaves and said anchoring points, and cable brackets mounted on the upper door section adjacent said hinged connection and having a cable restraining portion cooperating with the otherwise straight runs of said cable to divert the same and simultaneously to impose an inwardly biasing force on said top section to direct the upper edge of the same inwardly along said horizontal tracks as the door is moved into open position and to restrain forward movement of said upper edge as said door is moved into closed position.

2. An upward acting door assembly comprising a pair of horizontal tracks, an additional pair of tracks underlying said horizontal tracks and including vertical legs, horizontal legs, and curved portions connecting said legs, an articulated door having the upper section thereof mounted for movement along said horizontal tracks and the lower section thereof mounted for movement along said additional tracks, spring-tensioned cables for raising said door from closed vertical position to open overhead position, and cable pick-up brackets on the upper door section immediately above the joint between the sections to form short lever arms between the pick-up brackets and the joint, said brackets deflecting the run

70
75

of said cable to maintain an inward pull on the lever arms for initiating opening movement of the door by urging the upper edge of the upper section inwardly along said horizontal tracks.

3. In an upward acting closure construction including a closure, a pair of horizontal tracks supporting the top portion of the closure for movement inwardly from a doorway, a second pair of tracks supporting the other portion for upward and inward movement relative to the doorway, and spring-tensioned cables anchored on the lower portion of the closure, the improvement comprising cable pickup brackets mounted on the upper portion of the closure to form lever arms between the pickup brackets and the junction between the top portion and the remainder of the closure, said pickup brackets deflecting the run of the cables for producing a desired inward component of force on the lever arms, each of said pickup brackets comprising a member having a leg portion adapted to overlie the inner face of the closure and a U-shaped portion on said leg portion adapted to surround the track guiding the closure, and said U-shaped portion having a recessed lip on the free end thereof arranged to pick up one of the spring-tensioned cables.

4. An upward acting closure construction comprising a closure, a pair of horizontal tracks supporting the top portion of the closure for movement inwardly from a doorway, a second pair of tracks supporting the other portions for upward and inward movement relative to the doorway, spring-tensioned cables anchored on the lower portion of the closure, and cable guide brackets mounted on the upper portion of the closure, said guide brackets having a cable restraining portion cooperating with the otherwise straight runs of said cables to divert the same for producing an inward component of force on the top section to divert the upper edge of the same inwardly along said horizontal tracks as the door is moved into open position and to restrain forward movement of said upper edge as said door is moved into closed position.

5. An upward acting door construction for a doorway having door jambs along the side thereof comprising a plurality of hinged door sections, guide tracks mounted on the door jamb, rollers on said door sections cooperating with said tracks to guide the door between open and closed positions, a spring-tensioned cable anchored to the lowermost of said door sections, a sheave disposed inwardly from the top of the doorway receiving said cable therearound, a guide bracket on the uppermost of said door sections forming a lever arm between the guide bracket and the junction between said door sections and the remainder of the door, said guide bracket being arranged to receive said cable thereover and deflect the run of said cable between the sheave and lowermost door section to maintain an inward force on the lever arm, and a latching device on said uppermost door section for latching the door in closed position, said uppermost section being held in closed position against the inward pull of said spring-tensioned cable by said latching device whereby, when said latching device is released, said cable acting on said lever arm will pivot the top edge of said uppermost section inwardly independently of any further force being applied to open the door.
